UNITED STATES PATENT OFFICE.

JOHN E. SWANSON, OF JAMAICA PLAIN, MASSACHUSETTS.

CAST-METAL CUTTING DIE AND PROCESS OF PRODUCING THE SAME.

Application filed October 7, 1922. Serial No. 592,998.

To all whom it may concern:

Be it known that I, JOHN E. SWANSON a citizen of the United States, and resident of Jamaica Plain, county of Suffolk, State of Massachusetts, have invented an Improvement in Cast-Metal Cutting Dies and Processes of Producing the Same, of which the following description, in connection with the accompanying drawing, is a specification, 10 like characters on the drawing representing like parts.

This invention relates to improvements in processes for casting hollow articles and more particularly relates to processes for 15 casting hollow cutting dies such as are used in cutting leather and other materials into predetermined forms as for soles and uppers of shoes, etc.

In the manufacture of shoes and like articles where different sizes are made, large 20 numbers of different sizes and forms of dies are required. Such cutting dies have heretofore been produced by forging strips of steel to correspond to the form of a templet 25 and welding the edges together. This requires highly skilled labor and the production is very slow indeed. The object of the 30 present invention is to provide a simple and convenient process and means for readily and accurately producing cutting dies and like articles by casting molten material, preferably in a sand mould.

Certain of the dies used in cutting leather and like articles have been provided with a 35 central handle which is connected to a spider, the ends of which are welded to the upper portion of the die. A further object of the present invention is to produce a handle die in which the spider or the handle and 40 spider together are cast integrally with the die.

Other objects and features of the invention will more fully appear from the following description and the accompanying drawing 45 and will be pointed out in the claims.

The accompanying drawing is designed to illustrate the steps in the process for producing a cast metal cutting die in accordance with the present invention and also illustrates one form of die which can be made 50 in accordance with said process.

In the drawing:

Fig. 1 is a vertical sectional view of a three-part flask showing assembled therein 55 the platen, a series of units assembled there-

upon, said units corresponding in cross section to like portions of the die and the spider and handle all embedded in the members of the three-part flask;

Fig. 2 illustrates a preferred form of templet having a number of units corresponding to sections of the die assembled thereupon; 60

Fig. 3 is a vertical sectional view corresponding to Fig. 1 in which the cope, cheek and drag sections of the mould are separated 65 in superposed relation, the templet and units of the pattern having been withdrawn, whereby the flask when assembled will be ready to receive the molten metal; and,

Fig. 4 is a perspective view of a handle die 70 produced by the process embodying the invention in the flask and mould illustrated in Figs. 1 and 2.

The present invention comprises certain improvements upon the invention disclosed 75 in Patent No. 1,365,075 granted January 11, 1921, to Carl G. Anderson and John E. Swanson for processes and apparatus for producing cutting dies and consists mainly in a simplification of the process disclosed 80 in that patent.

Broadly speaking, the present invention consists in providing a novel process of forming a mould cavity for a die or other hollow article in a sand flask in such a 85 manner that the article can be readily cast therein, and further in providing a process for producing an integral handle cutting die. This process consists in a certain arrangement of a templet and associated pattern 90 units so devised that they can be readily manipulated to produce a sand mould into which molten metal or other material may be cast to form the desired hollow article. In order more fully to disclose the invention 95 the apparatus used in the performance of the process is illustrated herein.

In the performance of the process a usual multi-part flask is employed such as are commonly used in foundries. This flask as 100 illustrated in the accompanying drawing is a three-part rectangular flask. The lower member 1 or drag of the flask is shown as resting upon a suitable board or base 2 and having superimposed thereupon the intermediate section or cheek 3 upon which the upper member or cope 4 of the flask is superimposed. The cheek member of the flask is provided with metal brackets 5 having upwardly and downwardly extending pintles 110

6 and 7 adapted to pass respectively through apertures in brackets 8 and 9 upon the cope and drag as is usual in flask constructions.

In the performance of the process the lower or drag member 1 is filled with molding sand 10, preferably substantially even with its top, and covered with the usual parting material. A templet is placed upon the sand bed 10 thus formed. This templet desirably is in the form of a block 11 which has a contour substantially conforming to the contour of the article to be formed.

As illustrated in Fig. 2 the templet 11 is in the form of a shoe sole and for convenience and accuracy in construction has secured to its top and bottom patterns 12 and 13 which are produced accurately upon the usual pattern grading machines, the margin of the patterns 12 and 13 preferably extending slightly beyond the wall of the block 11. The templet thus formed is placed upon the upper surface of the sand bed 10. A series of units 14, having a cross section corresponding to the cross section of like portions of the die to be cast, are assembled upon this templet with their edges juxtaposed. The cheek member of the mould is then filled with a body 15 of sand and suitably tamped therein.

A pattern 16, corresponding to a reinforcing spider for the die or to the spider for a handle die, is then placed upon the top of the platen and units as illustrated in Fig. 1. Where a handle die is to be used a conical pattern member 17 is assembled upon the spider pattern and the cope member of the mould then filled with a body of sand 18 and properly tamped. When this is done the conical pattern 17 is withdrawn, the cope member raised, removed and reversed and the pattern 16 withdrawn therefrom.

The templet is then withdrawn from the cheek member and the space occupied by it filled with a body of sand 19 to form a core for the hollow article or die. The units 14 are thereupon withdrawn, thereby leaving a continuous cavity extending entirely through the cheek member.

By reason of this construction the cheek member can be readily removed and the outer wall of the die, which is represented by the inner face of the layer of sand, can be smoothed by the usual foundry slicking tool. The inner wall of the mould cavity, which is the outer wall of the body 19 of sand, is likewise readily accessible to the founder and can likewise be easily smoothed with the slicking tool. When this is accomplished the cheek member may be replaced, the proper mould cavity for the die or other article being thereby produced. The cope may then be assembled on the cheek member of the flask and the molten material poured in the usual manner.

By reason of this construction the mould produced will be that illustrated by Fig. 3 when the mould sections are considered as superimposed one upon the other and will comprise a continuous cavity 20 corresponding to the blade of the die with cavities 21 and 22 for the spider arms extending therefrom to the conical central aperture 23 which may be employed in place of the usual gate or sprue hole, thereby effecting the saving of the metal which usually constitutes the sprue of a casting.

The molten metal, upon being poured into the handle gate which corresponds to the sprue hole, runs readily along the cavities 20 for the spider arms into separated portions of a cavity for the blade. By thus supplying the cavity for the blade with metal at separated intervals a more perfect continuous casting is assured than if the metal were poured in at one or two places from different sprue holes supplied at different times. By the process above described dies and other hollow articles can be cast with great accuracy so that it is seldom necessary to reject a defective casting.

The handle die cast in the manner above described is illustrated in Fig. 4 and comprises a continuous blade 24 to the upper edge of which extend arms 25, 26 and 27 which radiate from a central hub 28 and a handle 29 which is integral with the hub. Thus by the novel process described a novel integral cutting die may be produced which is less expensive to manufacture and is accurate in construction. By the process above described the difficulties which attended the production of cast metal dies have been eliminated and the practical and commercial production of cutting dies and like articles assured.

It will be understood that the apparatus for performing the process and the steps of the process herein recited may be modified within the meaning and scope of the claims.

Having thus described my invention, what I claim as new, and desire to secure by Letters Patent, is:

1. The process of moulding hollow articles which consists in placing in a suitable mould a templet having a contour conforming substantially to the inner wall or walls of the article, arranging upon said templet a series of juxtaposed units corresponding in cross section to like portions of the wall or walls of the article to be cast, filling the mould with sand, removing the templet, filling the space occupied by the templet with sand to form a core, withdrawing the units and pouring the molten material to form the article into the mould thus produced.

2. The process of casting hollow cutting dies which consists in arranging within a sand mould a series of units juxtaposed at

their edges and having a cross section corresponding to like portions of the die, filling the mould with sand, removing said units, slicking the mould cavity thus produced and 5 pouring the molten material into the mould cavity thus produced.

3. The process of casting hollow cutting dies which consists in placing within a suitable mould a templet having a contour 10 conforming substantially to the inner wall of the die, arranging upon said templet a series of units corresponding in cross section to like portions of the wall of the die, filling the mould with sand, removing the templet, 15 filling the space occupied by the templet with sand to form a core, withdrawing the units, reassembling the mould and pouring the molten metal to form the article into the mould cavity thus produced.

20 4. The process of casting hollow cutting dies in a suitably parted three-part flask which consists in substantially filling the drag portion of the flask with sand and placing within the cheek portion of the flask 25 a block having upper and lower templets conforming substantially to the inner wall of the article, arranging upon said templets a series of juxtaposed units corresponding in cross section to like portions of the die, 30 filling the cheek portion with sand, withdrawing the templet and filling the space occupied thereby with sand, superimposing the cope upon said cheek member and filling the same with sand, withdrawing said units, 35 replacing said cope and pouring the molten metal into the die cavity thus formed through a suitable gate in said cope.

5. The process of casting hollow cutting dies in a three-part flask which consists in

forming by a pattern in the cheek member of 40 the flask a mould cavity corresponding in cross section to that of the die and extending through the sand of said cheek member, withdrawing the pattern, removing the cheek member, slicking the outer wall of the 45 mould cavity carried thereby and the inner wall of the cavity supported by the drag member of the flask, replacing the cheek member and cope and pouring the molten metal into the mould cavity thus formed 50 through a suitable gate in said cope.

6. The process of producing handle cutting dies in a three-part flask which consists in substantially filling the drag member of 55 the flask with sand, placing within the cheek member a templet corresponding in contour with the inner wall of the cutting die, assembling upon said templet a series of units corresponding in cross section to like portions of the die, filling the cheek member 60 with sand, removing the templet and filling the space occupied thereby with sand, placing upon the assembled units the pattern of the handle member comprising a spider and a handle extending from the hub thereof, removing the cope, withdrawing the pattern therefrom, withdrawing the units to leave a mould cavity for the die, removing the cheek section to permit the slicking of the outer wall of the mould cavity contained 70 in said cheek member and the inner wall of the mould cavity carried by the drag member, reassembling the flask and pouring the molten metal through the sprue hole of the cope member. 75

In testimony whereof, I have signed my name to this specification.

JOHN E. SWANSON.
